ANIMATED TOY

Towner H. Phillips, Portland, Oreg.

Application November 9, 1946, Serial No. 708,894

4 Claims. (Cl. 46—104)

1

This invention relates to an animated toy and has particular reference to a toy in the form of an animal which has a characteristic and realistic motion as it is caused to move across a surface.

It is an object of the invention to provide a toy of simple, inexpensive and durable construction which, when drawn or pushed across a surface, will respond with characteristic movements simulating those of an animal in motion.

The foregoing and other objects of the invention are accomplished by the provision of an animated toy, the construction of which is clearly disclosed in the following description, and the novel features of which are particularly pointed out in the appended claims, reference being had to the accompanying drawing wherein:

Fig. 1 is a side elevation of the animated toy of the invention, represented in the form of a dog.

Fig. 2 is a plan view thereof.

Fig. 3 is a longitudinal sectional view taken along the line 3—3 of Fig. 2.

Fig. 4 is a broken horizontal sectional view taken along the line 4—4 of Fig. 3 and showing in detail part of the animating mechanism.

As illustrated in the drawing, the animated toy of the invention comprises a horizontally elongated body portion 10, mounted on two pairs of wheels, one pair 11 being located toward the fore part of the body and the other pair 12 being positioned toward the rear. The body is formed with a longitudinal groove 13 in its underside within which is positioned an elongated member 14 of sufficient length so that both ends extend beyond the body portion 10. The rear end of the elongated member defines a tail 15, while the forward end defines a neck and lower jaw 16 and supports the head.

The head comprises a forward or nose portion 17 and two opposite side portions 18 and 19, the latter extending downwardly to form therebetween a groove or slot adapted to receive the forward part of the elongated member 14 on which the head is pivotally mounted, as by a pivot pin 20 extending at substantially right angles through the opposite side portions 18 and 19 and through the elongated member 14. Ears 21 depend freely from pivot pins 22 driven into the upper portion of the head and extend downwardly a substantial distance.

The elongated member 14 is supported slidably by front axle 23 and is attached to actuating means comprising the crank portion of the rear axle 24 by any desired means such as the staple 25.

2

When the figure is caused to move across a surface, as by pulling across a floor by means of a string 26, attached to the staple or eye 27, rotation of the rear wheels 12 induces rotation of the crank 24 thereby causing elongated member 14 to move back and forth within the groove 13. Rotation of the crank 24 also imparts a rotary motion to the rear end of the elongated member and as a result, the tail of the figure is caused to move up and down and in and out of the body. The pivot pin 20 is substantially in vertical alignment with the center of gravity of the head assembly so that upon reversal of movement of the elongated member 14, the momentum of the head 15 will carry it over the dead center position to the opposite position of rest. Upon repeated to and fro movement of the member 14, the head will rock back and forth accompanied by swinging movement of the ears upon their supporting pins 22 and opening and closing movement of the mouth of the animal. As the toy moves across the floor there is thus caused a motion of tail and head which is both realistic and amusing.

Although the features of the invention have been described and illustrated herein with particular reference to the figure of a dog, it is to be understood that no limitation is intended thereby, and that these features are suited equally well for application to divers other types of figures.

Having now described my invention, what is claimed as new and desired to protect by Letters Patent is:

1. An animated toy mounted on wheels comprising a horizontally elongated body portion having a longitudinal groove in the bottom thereof, an elongated member positioned within said groove and extending rearwardly from said body portion to form a tail section and forwardly from said body portion to form neck and lower jaw sections, a head mounted by transverse pivot on the forward end of said elongated member to cooperate with said lower jaw section in simulation of a mouth, ears pivotally mounted on either side of said head, and means for reciprocally actuating said elongated member.

2. An animated toy mounted on wheels comprising a body, wheels supporting said body, a longitudinal groove in the lower portion of said body, an elongated member positioned within said groove, said elongated member extending rearwardly from said body to form a tail section and forwardly from said body to form neck and lower jaw sections, a head mounted by transverse pivot on said neck section to cooperate with said lower

jaw section in simulation of a mouth, ears pivotally mounted on either side of said head and depending therefrom, and crank means for reciprocally actuating said elongated member.

3. An animated toy mounted on wheels comprising a horizontally elongated body, wheels supporting said body, a crank connected to at least one of said wheels, an elongated member positioned in the lower portion of said body and attached to said crank for longitudinal reciprocation of said elongated member, said elongated member extending rearwardly from the body to form a tail section and forwardly from the body to form neck and lower jaw sections, and a head mounted by transverse pivot on the forward end of said elongated member to cooperate with said lower jaw section in simulation of a mouth.

4. An animated toy mounted on wheels comprising a horizontally elongated body mounted on wheels, one pair of said wheels being located forwardly on said body and connected through an axle and another pair of said wheels being located rearwardly on said body and connected through

a crank, said body having a longitudinal groove in the underside thereof, an elongated member slidably supported within said groove by said axle and operatively associated with said crank to cause longitudinal reciprocation of said elongated member, said elongated member extending rearwardly from said body to form a tail section and forwardly from said body to form neck and lower jaw sections, a head mounted by transverse pivot in substantially balanced relationship upon the forward end of said elongated member to cooperate with said lower jaw section in simulation of a mouth.
